UNITED STATES PATENT OFFICE.

EARL G. WATROUS, OF HOOSICK FALLS, NEW YORK, ASSIGNOR TO THE
WALTER A. WOOD MOWING AND REAPING MACHINE COMPANY, OF
SAME PLACE.

HARVESTER.

SPECIFICATION forming part of Letters Patent No. 425,529, dated April 15, 1890.

Application filed November 23, 1889. Serial No. 331,812. (No model.)

To all whom it may concern:

Be it known that I, EARL G. WATROUS, a citizen of the United States, residing at Hoosick Falls, county of Rensselaer, and State of New York, have invented certain new and useful Improvements in Harvesters, of which the following is a full, clear, and exact description, reference being had to the accompanying drawings, forming a part of this specification.

My present invention relates more particularly to that type of harvesters used in connection with automatic grain-binders, and known in the art as "low-down" machines, although some of its features may be successfully applied to other types of harvesters.

In the drawings the driving-wheel is represented as mounted in a frame which is pivoted at its rear to the platform-frame and at its front to the tongue-frame. This frame is free at the will of the driver to be oscillated on the axle of the driving-wheel as a pivot.

This invention consists in a novel raising and lowering and tilting device, and also in the mechanism used to transmit motion from the driving-wheel to the operating devices carried on the platform-frame, which mechanism is of such a construction that its operation is not disturbed, irrespective of the position which the platform-frame may assume.

In order that others skilled in the art to which my invention appertains may readily understand the same, I will now more particularly describe it.

Referring to the accompanying drawings, in which only so much of a harvester is shown as is necessary to illustrate my invention, and in which similar letters of reference indicate like parts, Figure 1 is a top plan view. Fig. 2 is a side elevation. Figs. 3 and 4 are perspective views of details of the raising and lowering devices. Fig. 5 is a view in perspective of details of the driving mechanism.

A is the front longitudinal sill of the platform-frame.

B is the wheel or main frame.

C is the pole or tongue frame.

The main frame is pivoted to the front longitudinal sill A of the platform-frame or to brackets attached thereto at a a', upon which

pivots a a' the platform-frame is tilted with respect to the main frame B, in order to change the angle of inclination of the platform-frame, and consequently of the cutting apparatus. The main frame B is pivoted to the tongue-frame at c c'. Both the platform-frame and the main frame are rocked on the axle d of the driving-wheel D to change the height of the cutting apparatus.

E is a lever pivoted to the front of the main frame on a stud e, secured in the frame B. The hub of the lever E is formed hollow to receive a stiff spiral spring e', which is coiled around the stud e, and has one end e² projected through a slot e³ in the hub of the lever E. The other end of the spiral spring e' is secured to a segment F, pivoted also on the stud e. The segment F is formed with two segmental racks f f', which are engaged, respectively, by the spring-detents g g'.

A rod G is connected at g² to an upright G', supported from the front longitudinal side of the platform-frame, from which it extends forwardly and is bent at right angles at its front end, where it is pivoted in a bracket H, attached to lever E. The bracket H is provided with two adjusting-holes h h', for the purpose of changing the range of adjustment of the platform-frame. It is evident that by swinging the lever E on the stud e as a pivot the platform-frame will be rocked on its pivotal connections a a' with the main frame, and the angle of inclination of the cutting apparatus carried on the platform-frame be changed.

Inasmuch as the rear end of the platform-frame, by reason of the platform being pivoted at its front end, has a tendency to drop, I have applied the spring e', as shown, so that its expansion will assist the operator in tilting the points of the guards downwardly. The spring e' when put in place is coiled or compressed sufficiently so that when the lever E is free to rock on its pivot e and with regard to the segment F, the expansion of the spring will tend to tilt the points of the guards downwardly and the rear end of the platform upwardly. The lever E extends beyond its pivot e and carries a detent g, pivoted thereto at g³. A spiral spring e⁴ is interposed be-

tween a lug e^5 on the detent and a corresponding lug e^6 on the lever E. The spring e^4 acts to force the detent g into engagement with the rack f . A rod e^7 is connected to the detent g and to a suitable hand-lever carried on the top of the lever E, by which the detent may be disengaged from the rack f , when the lever E will be free to be rocked on the stud e . The segment F is perforated at f^2 , 10 and receives one end of the link F' , the other end of which is pivoted in a standard F^2 , attached to the tongue-frame. It is evident that the rocking of the segment F on the stud e will, through the link F' , rock the main frame, together with the platform-frame connected therewith, thereby raising or lowering the height of the cutting apparatus. The segment F is normally held rigid with respect to lever E by the detent g' , which is pivoted between the flanges g^4 g^5 of segment F, and is 15 forced by the spring g^6 , interposed between the detent and a lug on the segment F, into engagement with the rack f' . The detent g' is connected by a rod g^7 with a foot-lever g^8 , mounted on the pole-frame and within reach of the driver on his seat. By means of the lever g^8 and the rod g^7 the detent g' is released from the rack f' , and the detent g being left in engagement with the rack f , the movement of 20 the lever E will carry with it the segment F, and the main frame through the link F' will be rocked on the axle of the driving-wheel. Of course it will be understood from the previous description, taken in connection with 25 the drawings, that when it is desired to tilt the platform-frame on its pivotal connections with the main frame, the detent g' is left in engagement with the rack f' and the detent g disengaged from the rack f ; also that to 30 raise and lower the platform-frame or to rock it on the axle of the driving-wheel, the detent g will be left in engagement with the rack f and the detent g' disengaged from the rack f' , the rocking of the lever E serving 35 both to tilt and to raise or depress the cutting apparatus.

From an inspection of the drawings it will be noticed that when the main frame is rocked on the axle of the driving-wheel the angle of 40 inclination of the platform, were the link or rod G attached to the pole-frame or to the axis of movement of the lever E, would be changed. If, however, it is desirable that the platform should, during the rocking of the 45 main frame, maintain a uniform position with reference to the ground, this can be accomplished by placing the bracket H of the lever E, in which is pivoted the forward end of the rod G, at the requisite distance from the pivot 50 e of the lever E, so that the backward movement of the lever E and the rod G will rock the platform-frame on its pivotal connections with the main frame enough to compensate 55 for the inclination given to the platform-frame by its rocking on the axle of the driving-wheel. The distance of the pivot of the rod G in bracket H from the pivot of the lever E

to produce this result—i. e., the uniform position of the platform with respect to the ground—depends upon the movement of the 70 lever E necessary to rock the main frame a certain distance, and the distance of the pivotal point of attachment of the platform and main frame to the connection of the rod G with the platform-frame. 75

In the drawings I have shown the rod G attached to lever E at a sufficient distance from the pivot of the latter to lower the rear end of the platform when the main frame is raised on the axle of the driving-wheel, which construction is advantageous, as it brings about the tilting of the points of the guards or the cutting apparatus when the lever E is moved so as to lower the platform-frame, the main frame rocking about the axle of the driving-wheel. The lever E, it will be noticed, and the front of the main frame, move in opposite directions. When the lever is raised, the front of the main frame is lowered, and consequently the rear of the main frame elevated, and vice versa. 85 When the rear end of the main frame, and consequently the platform-frame, is raised by lever E, the position of the platform may be regulated by letting the detent g' into engagement with rack f' , releasing the detent g from rack f , and then moving the lever E to bring the platform in any desired position. It is evident that by this arrangement the position of the platform may be uniform, its rear end may be depressed or elevated, according 90 to the distance of the point of attachment of the rod G to the bracket H from the pivot e as the main frame is rocked on the axle of the driving-wheel to raise the rear end of the main frame; or that if the main frame is 95 rocked in the opposite direction the position of the platform may be uniform or its rear end elevated or depressed. All of these results may be accomplished by the same arrangement—i. e., the rocking lever on the 100 main frame connected to both the pivoted platform-frame and to the pivoted tongue-frame.

In order that the platform-frame may be tilted on its pivotal connections with the main frame and the operative relation of the operative mechanism carried on the platform-frame and the driving-shaft in the main frame may not be disturbed, the following construction is employed: 115

A shaft J is mounted in suitable bearings in the main frame, and the shaft is provided on its forward end with a gear or pinion J' , which meshes with a bevel-gear J^2 , mounted on the axle of the driving-wheel and receiving its motion by any suitable clutch mechanism therefrom. The shaft J is parallel with the advance of the machine, and at its rear end carries an internal bell-mouthing gear J^3 , provided with cog-teeth J^4 . 120

Mounted on a stud rigidly secured to the front of the platform-frame is a sprocket-wheel J^5 , provided with an elongated hub J^6 , which has on its forward end the elliptically-shaped 130

teeth J^7 , which take into the bell-mouthing gear J^3 . The articulation between the bell-mouthing gear J^3 and the teeth J^7 is in line with the pivotal connections a a' of the platform 5 and main frames. A sprocket-chain passing over the sprocket-wheel J^5 serves to communicate motion to the various operative devices carried on the platform-frame. It is evident that the platform-frame under this construction 10 may be tilted on its pivotal connections with the main frame without disturbing the driving relation of the shaft J . It will also be noticed that as the platform-frame tilts on its pivotal connections with the main frame 15 the elliptical teeth J^7 are free to roll or rock on the teeth J^4 , and that owing to this elliptical shape the bearing-surface of the bell-mouthing gear on the teeth J^7 is not decreased as the platform-frame is tilted. The 20 shaft J , being mounted in the main frame, swinging or rocking on the axle of the driving-wheel, partakes of the movement of the main frame and the gears J^1 J^2 are always kept in mesh.

25 Having now described my invention, what I claim as new, and desire to secure by Letters Patent, is—

1. The combination, in a harvester, of the main frame, the platform-frame and pole-frame pivoted, respectively, in rear and front thereof, a lever on the main frame, a link connecting the lever and platform-frame, a locking device connecting the lever to the main frame, a second link connected to the 30 pole-frame, and a locking device connecting the second link and the lever, substantially as and for the purpose described.

2. The combination of the main frame rocking on the axle of the driving-wheel, the platform-frame pivoted thereto in rear thereof, the tongue-frame pivoted thereto in front thereof, a lever mounted on the main frame, a segmental rack mounted concentrically with the lever, a link connecting the pole-frame and the segmental rack, a link connecting the platform-frame and the lever, a detent mounted on the lever to engage the segmental rack, and a second detent on the main frame to lock the segmental rack in a 45 fixed position with regard to the main frame.

3. The combination of the main frame rocking on the axle of the driving-wheel, the tongue-frame pivoted thereto in front thereof, the platform-frame pivoted thereto in rear thereof, a rocking lever mounted on the main frame, a segment pivoted concentrically with the axis of movement of the lever, two segmental racks on the segment, a detent mounted on the lever to engage with one segmental 50 rack to lock the latter fast with the lever, a detent on the main frame to engage the other segmental rack, a link connected with the tongue-frame and the segment, a second link connected to the lever and the platform-frame, and means to disengage the detents from the racks, whereby the lever is adapted to both tilt the platform-frame on its pivotal 55

connection with the main frame and to rock the latter, together with the platform-frame, on the axle of the driving-wheel, substantially as and for the purpose specified.

4. The combination of the main frame rocking on the axle of the driving-wheel, the tongue-frame pivoted thereto in front thereof, and the platform-frame pivoted thereto in rear thereof, a rocking lever on the main frame, a segment pivoted concentrically with the axis of movement of the lever, a detent on the lever taking into a rack in the segment, a detent on the main frame taking into a second rack on the segment, a spring secured to the lever at one end and to the segment at the other, a link connected to the segment and the tongue-frame, a second link connected to the platform-frame and to the lever, and means to disengage the detents from the racks, whereby the spring assists in tilting the platform-frame on its pivotal connections with the main frame and does not interfere with the rocking of the machine on the axle, substantially as specified.

5. The combination of the main frame rocking on the axle of the driving-wheel, the platform-frame pivoted thereto in rear thereof, and the tongue-frame pivoted thereto in front thereof, a lever pivoted on the main frame, a segment pivoted concentrically with the axis of movement of the pivoted lever, a link connecting the lever and platform-frame, a link connecting the segment and tongue-frame, and means for locking the segment to the lever and the segment to the main frame, substantially as and for the purpose specified.

6. The combination of the main frame, the platform-frame pivoted thereto in rear thereof, the driving-wheel and its driving-gear mounted in the main frame, a counter-shaft mounted in the main frame parallel with the advance of the machine, a gear thereon meshing with the driving-gear, and a communicating-shaft on the platform-frame articulated by a universal joint with the counter-shaft in line with the pivotal connections of the main and platform frames, substantially as and for the purpose specified.

7. The combination of the main frame, the driving-wheel and its driving-gear mounted thereon, a counter-shaft mounted in the main frame parallel with the advance of the machine, a gear on the forward end of the counter-shaft meshing with the driving-gear, the platform-frame pivoted to the main frame, a bell-mouthing gear on the rear end of the counter-shaft, and a communicating-shaft on the platform-frame having a hub with elliptical gear-teeth taking into the bell-mouthing gear in the line of the pivotal connection of the main and platform frames, substantially as and for the purpose specified.

8. The combination, with the main frame, of the driving-wheel and its driving-gear mounted thereon, a counter-shaft mounted in the main frame parallel with the advance of the machine, a gear on the forward end of the

counter-shaft meshing with the driving-gear, the platform-frame pivoted to the main frame, a communicating-shaft on the platform-frame articulating by a universal joint with the counter-shaft in the main frame in line with the pivoted connection of the main and platform frames, and a lever for tilting the platform-frame, as and for the purpose specified.

9. The combination, with the main frame, of the platform-frame pivoted thereto, a driving-shaft in the main frame parallel with the advance of the machine, and a communicating-

shaft on the platform-frame articulating by a universal joint in line with the pivotal connections of the main and platform frames ¹⁵ with the driving-shaft, substantially as and for the purpose specified.

In witness whereof I have hereto set my hand this 21st day of November, 1889.

EARL G. WATROUS.
